UNITED STATES PATENT OFFICE.

ALBERT A. UNRUH, OF PORTLAND, OREGON, ASSIGNOR OF ONE-HALF TO E. J. VENNEWITZ, OF PORTLAND, OREGON.

GARAGE-DOOR OPENER.

Application filed November 3, 1921. Serial No. 512,576.

To all whom it may concern:

Be it known that I, ALBERT A. UNRUH, a citizen of the United States, residing at Portland, in the county of Multnomah and 5 State of Oregon, have invented certain new and useful Improvements in Garage-Door Openers; and I do declare the following to be a full, clear, and exact description of the invention, such as will enable others skilled 10 in the art to which it appertains to make and use the same.

My invention relates to improvements in door releasing and operating means and more particularly to those intended primarily for use upon hinged garage doors.

The principal object of the invention is to provide a novel releasing means for the door or doors which is controlled by depressible members at the outside of the garage so as to 20 automatically release the doors and permit them to open when a machine is driven up to enter the garage, novel provision being made, however, whereby the operating connections may be rendered inoperative at the 25 will of the operator, so that no unauthorized person may open the garage and remove the machine.

With the foregoing in view, the invention resides in the novel subject matter herein- 30 after described and claimed, the descriptive matter being supplemented by the accompanying drawings.

Figure 1 is an inner side elevation of a pair of doors and their frame showing the 35 application of my invention thereto.

Figure 2 is a horizontal sectional view as indicated by line 2—2 of Fig. 1, a portion of the approach to the garage being broken away.

40 Figure 3 is a vertical sectional view as indicated by line 3—3 of Fig. 1.

Figure 4 is a plan view of the outer end portion of the approach and the depressible operating members thereon for the door re- 45 leasing means.

Figure 5 is an elevation of the lower side of the sliding plates which co-operate in forming a keeper for the locking bolt carried by one of the doors.

50 Figure 6 is a sectional view as indicated by line 6—6 of Fig. 5.

Figure 7 is a perspective view of the device for rendering the operating connections either inoperative or operative, as desired.

Figure 8 is a vertical sectional view of the 55 device shown in Fig. 7.

Figure 9 is a horizontal sectional view on line 9—9 of Fig. 8.

In the drawings above briefly described, the numeral 1 designates a door frame to 60 which a pair of doors 2 and 2^a are hinged, the upper end of the door 2 being provided with a well known latch 3 for securing it to the frame, while the door 2^a is equipped with a night latch 2^b for locking it to the door 2, 65 so that unless the latch 2^b is released, the door 2^a cannot be opened without first opening the door 2. To prevent opening of the door 2 however, by unauthorized persons, I provide an improved form of locking means 70 co-operable with the bolt 3. An elongated rectangular guide plate 4 is secured by screws or the like 5 to the crown of the frame 1, one longitudinal edge of said plate being provided with a notch 6 adapted to receive 75 the bolt 3, said edge being formed with guide flanges 7 at opposite sides of said notch. The other edge of the plate 4 is provided with a longitudinal guide flange 8 which terminates short of its ends as shown 80 clearly in Figs. 2 and 3. A pair of spring-pressed bolts are provided between the flanges 7 and 8, said bolts being preferably in the form of metal plates 9 whose inner ends are provided with notches 10 jointly 85 forming a keeper for the bolt 3. The outer ends of the plates 9 are provided with lateral ears 11 at the ends of the flange 8 and these ears are connected by a coiled spring 12 which normally pulls the plates 9 into 90 abutting relation with each other as shown, so that the bolt 3 will be held against outward movement to normally lock both doors in closed position.

A cable or the like 13 leads from the lug 95 11 of one of the bolts 9, is trained around suitable sheaves 14, and extends outwardly from the garage doors, at one edge of a suitable approach 15. Upon this approach, a pair of depressible operating members 16 100 are located, which are to be struck and depressed by the wheels of an approaching automobile. The members 16 are by preference in the form of metal plates secured upon rock shafts 17 which are mounted on the approach 15 in any suitable manner, the shafts 17 being provided with depending crank arms 18 to one of which the cable 13 is con- 105

- 13^a is connected the two cables 13 and 13^a being housed within pipes or the like 19 or protected in any other desirable manner. 5 The cable 13^a extends into the interior of the garage, is trained around a sheave 14^a and extends upwardly from this sheave to a coupling device 20 by means of which it is connected to a cable 13^b trained around an 10 upper sheave 14^b and connected with the lug 11 remote from the cable 13.

By the arrangement shown, when an automobile is driven to the garage and depresses the operating members 16 against the action 15 of the spring 16^a, the several cables are pulled upon so that both of the bolts 9 are released against the tension of the spring 12, the result being that the latch 3 is free to move outwardly to permit simultaneous 20 opening of the doors 2 and 2^a. This opening is effected by weights 21, cables 22 connected to said weights and trained over sheaves 23 and arms 24 on the doors to which said cables 22 are connected. To then 25 hold the doors in open position, particularly when a strong wind is blowing, the lower ends of said doors are provided with pivoted catches 25 which are adapted to engage stakes or the like 26.

30 When the machine has been driven into the garage, the coupling 20 may be rendered inoperative so that the simultaneous release of both bolts 9, which is necessary to open the doors of the garage, is prevented. This 35 coupling member is constructed in any suitable manner for accomplishing the desired results, but it by preference is formed in the manner shown. A tube 27 is connected by a bail or the like 28 to the cable 13^b, said 40 tube being provided in its lower portion with a longitudinal slot 29 having a lateral extension 30 at its upper end. A link 31 is slidably received in the tube 27 and is connected at its lower end with the cable 13^a, said link 45 having a lateral arm 32 positioned in the slot of the tube and received in the lateral extension 30 of said slot when the connection 20 is in operative condition, that is, when the machine is out of the garage. After the 50 automobile has been driven into the garage, however, the lateral arm 32 is moved out of the lateral extension 30 of the slot 29, with the result that any downward pull on the link 31, by means of the cable 13^a will merely 55 slide said link idly within the tube 27 and will not pull upon the cable 13^b to release the bolt 9 to which said cable 13^a is connected. It will be seen, however, that as long as the 60 arm 32 is in the lateral extension 30 of the slot 29, any pull upon the cable 13^a will correspondingly pull the cable 13^b to release the latch 9 above mentioned.

When the arm 32 of the link 31 is moved out of the extension 30 of the slot 29, the link 65 31 is supported by a coiled spring 31^a within

the tube 27 and any downward pull on said link will stretch this comparatively weak spring so that the cable 13^b will not be moved. In some instances, if desired, the 70 spring 31^a might well be omitted.

From the foregoing, taken in connection with the accompanying drawings, it will be seen that I have provided an extremely simple and desirable arrangement of parts for automatically opening a garage door when a 75 machine is driven up the approach thereto and for positively preventing release of the door locking means when the machine is in the garage. About three hundred pounds 80 weight is necessary to depress each of the operating members 16 and hence it is practically impossible for anyone to release the garage doors when the machine is out and the coupling 20 is in operative position, but as soon as the proper machine returns and 85 depresses the members 16, the doors will automatically open.

It will be understood that while one form of my invention has been disclosed, the device may be embodied in numerous other 90 forms within the scope of the appended claims.

I claim:

1. The combination with a door and a lock therefor, of an operating member disposed at the outer side of said door, and connecting means between said operating member and said lock comprising two operating connections movable relatively without releasing the lock, and means whereby 100 said connections may be operatively connected to permit said operating member to release the lock.

2. The combination with a door and a lock therefor, of an operating member disposed at the outer side of said door and connecting means between said operating member and said lock, convertible at will into an 105 elastic inoperative character or into an inelastic operative nature.

3. The combination with a door and a lock therefor, of an operating member disposed at the outer side of said door and lock-releasing pull means connecting said lock with said operating member and comprising a 115 pair of pull members, relatively movable coupling members connected to said pull members respectively, and means for positively connecting said coupling members with each other or for disconnecting them to prevent operation of said lock releasing pull means.

4. The combination with a door and lock therefor, of an operating member disposed at the outer side of said door and lock releasing pull means connecting said lock with said operating member and comprising a pair of telescopic coupling members and pull members connected respectively thereto, the outermost of said coupling members having a 120 130

longitudinal slot provided with a lateral throat, the innermost coupling member being provided with a lateral arm adapted for normal disposition in said lateral throat.

5. The combination with a door frame, a pair of hinged doors mounted on said frame, means for locking one door to the other, and a releasable latch on the upper end of said other door; of a pair of spring-pressed locking bolts at the upper end of the door frame, co-operating to form a keeper for said latch, cables connected with said bolts, guides over which said cables are trained with their ends depending at the sides of the frame, a pair 10 of depressible operating members spaced outwardly from said doors, one of said cables being connected to one of said members, an additional cable connected to the other operating member and extending into 15 the garage, and a coupling member connecting said additional cable with the other of said pair of cables, said coupling member

being formed of two members which may be quickly disconnected from operative engagement with each other.

25

6. A door release for co-action with a bolt on a door, comprising a rectangular plate adapted to be secured to the upper end of the door frame, one edge of said plate having a bolt receiving notch and being folded 30 on itself to provide longitudinal guide flanges at opposite sides of said notch, the other edge of said plate being folded upon itself to form an additional longitudinal guide flange which terminates short of the ends of said plate, a 35 pair of latch plates slidably mounted between said guide flanges and having bolt receiving notches in their inner ends, said latch plates being provided with lateral ears at the ends of said additional flange, and a tension 40 spring connecting said ears.

In testimony whereof I have hereunto set my hand.

ALBERT A. UNRUH.
